Primary Examiner — Ian Simmons*Assistant Examiner* — Rhea Shields(74) *Attorney, Agent, or Firm* — Dickstein Shapiro LLP(57) **CLAIM**

The ornamental design for a blister pack, as shown and described.

DESCRIPTION

FIG. 1 is a front view of the blister pack, showing the new design;

FIG. 2 is a rear view thereof;

FIG. 3 is left-side view thereof;

FIG. 4 is a right-side view thereof;

FIG. 5 is a bottom view thereof;

FIG. 6 is a top view thereof; and,

FIG. 7 is a rear, left side, and top perspective view thereof.

The blister pack is symmetrical about a vertical axis, such that

FIG. 4 is a mirror image of FIG. 3.
